ANIMAL FIGURE WHEELED TOY

Charles P. Hill, Nashville, Tenn., assignor to Kusan, Inc.,
Nashville, Tenn., a corporation of Kentucky

Filed Apr. 16, 1964, Ser. No. 79,521

Term of patent 14 years

(Cl. D34—15)

I claim:

The ornamental design for an animal figure wheeled toy, as shown.
